UNITED STATES PATENT OFFICE.

LAWRENCE E. FRENCH, OF LOS ANGELES, CALIFORNIA.

DESIGN FOR AN AUTOMOBILE-BODY.

44,760.

Specification for Design.

Patented Oct. 21, 1913.

Application filed August 25, 1913. Serial No. 786,624. Term of patent 7 years.

To all whom it may concern:

Be it known that I, LAWRENCE E. FRENCH, a citizen of the United States, residing at Los Angeles, in the county of Los Angeles, State of California, have invented a new, original, and ornamental Design for Automobile-Bodies, of which the following is a specification, reference being had to the accompanying drawing, forming part thereof.

Figure 1 is a side elevation of the auto-

mobile body. Fig. 2 is a plan view of the automobile body.

I claim:

The ornamental design for an automobile body as shown.

LAWRENCE E. FRENCH.
